UNITED STATES PATENT OFFICE.

WILLIAM JOSEPH STILL, OF TORONTO, CANADA.

STORAGE BATTERY.

SPECIFICATION forming part of Letters Patent No. 678,443, dated July 16, 1901.

Application filed March 24, 1899. Serial No. 710,355. (No model.)

To all whom it may concern:

Be it known that I, WILLIAM JOSEPH STILL, electrician, of the city of Toronto, in the county of York, in the Province of Ontario, Canada, have invented certain new and useful Improvements in Storage Batteries, of which the following is a specification.

My invention relates to improvements in storage batteries; and the object of the invention is to produce a light, compact, and durable cell capable of sustaining its voltage under very rapid discharges; and it consists, essentially, of electrodes of comb-like form, which are suitably held together at the bottom and the terminals separated from each other and supported by a suitably-slotted bar of insulating material and held from the bottom of the plate by an insulating-bar, the parts being constructed and arranged in detail as hereinafter more particularly explained.

Figure 1 is a perspective view of my improved storage cell, showing the arrangements of the electrodes, the cell being partially in section. Fig. 2 is a plan view. Fig. 3 is a detail showing the construction of the electrodes. Fig. 4 is a detail of the slotted insulating-bar.

In the drawings like letters of reference indicate corresponding parts in each figure.

Each electrode is formed with a back plate A, having stamped or formed out at the sides thereof the comb-like fingers or projections a. These fingers or projections are cut out on the flat by any suitable cutting mechanism and then are each turned at right angles to the plane of the plate A, after which both groups at each side are bent inwardly, as indicated in Fig. 3, so as to be at right angles to the main portion A of the plate. It will thus be seen that the fingers a, standing one directly above the other, present horizontal surfaces from end to end, between which is pasted the active material, as indicated in Fig. 1, in which a' is the active material.

The top of the plate A is provided with a terminal tongue A'. The two comb-like sides of the electrode are held together by the elastic bands B, which permit expansion and assist contraction. The bottom of each comb-like side of the electrode is supported upon the insulating-bar C, provided with a bent

end c and the bottom of the slotted bar D, which embraces the comb-like side of the electrode, the slot not extending to the bottom of the bar, thus holding the bar C away from the bottom of the cell.

I will suppose that A is the positive electrode-plate, and A² and A³ are other electrodes, formed precisely the same way with terminals A⁴ and A⁵. These electrodes are formed precisely the same way, with the exception that the comb-like sides a are at less distances apart. The terminal tongues are preferably soldered together and provided with a central hole.

a² represents lips forming part of the terminal tongues of the largest electrode-plate, which are bent around the terminal tongues A⁴ and A⁵.

a³ is a lip which forms part of the larger electrode and is bent around the bottom of the adjacent electrodes. This lip a³ is shown on the negative electrode, which I wish now to refer to.

E represents the negative electrodes, which are formed precisely the same way as the positive electrodes except the active material is different. The form of the terminal and of the other parts of the plate are precisely alike. The comb-like sides of each group of electrodes are so arranged and placed between each other that each adjacent side is of opposite polarity. The hole is made in the terminal of the plates A and E, the adjacent terminals of the positive plate of one cell being connected to the negative terminals of the next cell by a bolt and nut 2 3, extending through holes in the terminal tongues and formed of rubber.

By a construction such as I describe it will be readily understood that space is economized and the active material is preserved intact and the electrodes are necessarily very light. It will also be understood that each series of comb-like fingers with the interposed active material constitutes an electrode, and that such electrodes when formed in the U shape shown and described are arranged in pairs of like polarity joined together, so as to occupy the minimum space in the cell and yet serve to greatly promote the efficiency of the battery by the relatively large area of active material securely exposed

between the fingers of each series. The compactness and efficiency of the battery are also greatly promoted by the oppositely-disposed and similarly-constructed electrodes, all of which being **U**-shaped and those of each set fitting by pairs, one pair within the other, and arranged in staggered relation to the electrodes of the other set, takes up the minimum space while filling the same with great compactness, the insulating bars on the free end of each electrode serving the double purpose of sustaining the fingers in place and as separators for the electrodes.

I am aware that a comb-like plate formed with twisted bars constituting the core of an electrode and upon which the active material is held by separating plates has heretofore been proposed, and I am also aware that a series of bars have been formed in a rectangular frame by slitting a plate and turning the bars thus formed at right angles to the body of the plate, and I therefore do not claim such constructions, nor would such constructions subserve the purposes of my invention, nor do they enable the production of a battery possessing the many advantages of mine, nor one that may be as light, compact, or durable, or capable of sustaining its voltage under very rapid discharges, all of which are very essential points in both the practical and commercial value of a storage battery, particularly one adapted for use upon motor-vehicles.

What I claim as my invention is—

1. An electrode for storage batteries comprising a **U**-shaped plate having a body portion and a series of projections extending from opposite edges thereof, and at right angles thereto, forming a pair of parallel combs, said projections constituting supports for the active material and interposed therebetween, substantially as and for the purpose specified.

2. An electrode for storage batteries comprising a **U**-shaped plate having a body portion and a series of comb-like fingers projecting therefrom, at opposite sides thereof and at right angles thereto, said fingers being twisted so as to lie at right angles to the plane of said body portion and constituting a pair of parallel supports for the active material interposed therebetween, substantially as and for the purpose specified.

3. In a storage battery, a series of **U**-shaped electrodes fitting one within the other and each comprising a plate having a body portion and a series of comb-like fingers or projections at opposite edges thereof and extending at right angles to the body portion and a terminal on each of said body portions suitably connected together, said comb-like fingers constituting supports for the active material interposed therebetween, substantially as and for the purpose specified.

4. In a storage battery, a series of **U**-shaped electrodes fitting one within the other and each comprising a plate having a body portion, comb-like fingers or projections at op-

posite edges thereof and at right angles to the body portion, terminals at the top of said body portion of each plate suitably connected together and a lip at the bottom of the body portion of the outer plate, which spans and embraces the bottoms of the adjacent plates connected thereto, the comb-like fingers on each plate constituting supports for the active material interposed therebetween, substantially as and for the purpose specified.

5. An electrode for storage batteries comprising a **U**-shaped plate having a body portion and a series of comb-like fingers projecting therefrom at opposite edges thereof and at right angles thereto, said fingers constituting a pair of parallel supports for the active material interposed therebetween, and elastic bands embracing said comb-like fingers, substantially as and for the purpose specified.

6. An electrode for storage batteries comprising a **U**-shaped plate having a body portion and a series of comb-like fingers projecting therefrom at opposite edges thereof and at right angles thereto, said fingers constituting a pair of parallel supports for the active material interposed therebetween and a slotted insulating-bar fitted to embrace the free ends of each series of comb-like fingers, substantially as and for the purpose specified.

7. An electrode for storage batteries comprising a **U**-shaped plate having a body portion and a series of comb-like fingers projecting therefrom at opposite edges thereof and at right angles thereto, said fingers constituting a pair of parallel supports for the active material interposed therebetween, elastic insulating-bands embracing said comb-like fingers and a slotted insulating-bar fitted to embrace the free ends of each series of comb-like fingers, substantially as and for the purpose specified.

8. An electrode for storage batteries comprising a plate having a body portion and a series of comb-like fingers projecting therefrom at opposite edges thereof and at right angles thereto, said fingers constituting supports for the active material interposed therebetween, a slotted insulating-bar fitted to embrace the free ends of each series of comb-like fingers and the bottom insulating-bar forming a support for the fingers and provided with a bent end next the body portion of the plate, as and for the purpose specified.

9. An electrode for storage batteries comprising a plate having a body portion and a series of comb-like fingers projecting therefrom at opposite edges thereof and at right angles thereto, said fingers constituting supports for the active material interposed therebetween, elastic insulating-bands embracing said comb-like fingers, a slotted insulating-bar fitted to embrace the free ends of each series of comb-like fingers and the bottom insulating-bar forming a support for the fingers and provided with a bent end next the body portion of the plate, as and for the purpose specified.

10. In a storage battery, the combination of a series of electrodes each comprising two series of comb-like fingers joined in pairs by connecting-plates at right angles thereto, 5 each pair being placed between a wider pair of like polarity and the connecting-plates being electrically connected together, as and for the purpose specified.

11. In a storage battery, the combination 10 of a series of electrodes each comprising a series of comb-like fingers joined in pairs and constituting supports for the active material interposed therebetween, and each pair being placed between a wider pair of like polarity 15 and insulating slotted bars embracing the free ends of each series of fingers, substantially as and for the purpose specified.

12. In a storage battery, the combination 20 of a series of electrodes each comprising a series of comb-like fingers joined in pairs and constituting supports for the active material interposed therebetween, a bottom insulating-bar forming a support for the fingers and provided with a bent end next the connected 25 ends of the series of fingers, an insulating slotted bar embracing the free ends of each series of fingers and the bottom bar, substantially as and for the purpose specified.

13. In a storage battery, the combination 30 of a series of electrodes each comprising a series of comb-like fingers joined in pairs and constituting supports for the active material interposed therebetween, a bottom insulating-bar forming a support for the fingers and

provided with a bent end next the connected 35 ends of the series of fingers, elastic insulating-bands embracing each series of fingers and the bottom bar at each end thereof and an insulating slotted bar embracing the free 40 end of each series of fingers and the bottom bar, substantially as and for the purpose specified.

14. In a storage battery, the combination of two series of electrodes each comprising plates having a series of comb-like fingers or 45 projections at opposite edges thereof and at right angles thereto, said fingers being twisted so as to lie in planes at right angles to that of the plate, the series of comb-like projections in each set of electrodes being arranged in 50 staggered relation with those of the other set, substantially as and for the purpose specified.

15. In a storage battery, the combination of two series of electrodes each comprising plates having a series of comb-like fingers or 55 projections at opposite edges thereof and at right angles thereto, said fingers being twisted so as to lie in planes at right angles to that of the plate, the series of comb-like projections in each set of electrodes being arranged in 60 staggered relation with those of the other set, and insulating slotted bars embracing the free end of each series of fingers, substantially as and for the purpose specified.
